(57) **CLAIM**

The ornamental design for a wristband with sanitizer holder, as shown and described.

DESCRIPTION

FIG. 1 is a rear view of a wristband with sanitizer holder showing my new design;

FIG. 2 is a front view of the wristband with sanitizer holder;

FIG. 3 is a left side view of the wristband with sanitizer holder;

FIG. 4 is a right side view of the wristband with sanitizer holder;

FIG. 5 is a top view of the wristband with sanitizer holder;

FIG. 6 is a bottom view of the wristband with sanitizer holder;

FIG. 7 is a top rear side perspective view of the wristband with sanitizer holder; and,

FIG. 8 is a top front side perspective view of the wristband with sanitizer holder.

The broken lines in the drawings illustrate a boundary line and form no part of the claimed design.
